UNITED STATES PATENT OFFICE.

LOUIS B. MAY, OF PITTSBURGH, PENNSYLVANIA.

BOAT.

Application filed July 9, 1927. Serial No. 204,592.

The present invention relates broadly to the art of marine propulsion, and more particularly to an improved hull construction for vessels and to improved propelling means co-operating therewith.

It has heretofore been proposed, in the art to which the present invention relates, to effect the propulsion of boats by the provision of channels extending partly or entirely through the hull thereof and adapted to effect the discharge of a stream or streams of water in such manner as to produce a forward, rearward, flanking or turning movement.

It is one of the objects of the present invention to provide an improved construction operating on the general principle referred to and preferably embodying a plurality of flow passages occupying a minimum amount of room and located entirely in the forward part of the hull. The passages are conveniently so constructed that they intersect to form a chamber common to both of the passages, the chamber being provided with control means of such nature that a flow of water may be produced through either of the passages individually or through both of the passages simultaneously with any desired variation in volume of flow from minimum to maximum, the flow itself being produced by separate flow producing means located in the respective passages. By reason of such a construction, both of the flow producing means are effective simultaneously for flanking or turning, thereby enabling results to be obtained which have heretofore not been obtainable with other constructions.

In the accompanying drawings, there is shown, by way of illustration only, a preferred embodiment of the present invention, it being understood that the drawings do not define the limits of my invention as changes in the construction and arrangement of parts may be made without departing either from the spirit of the invention or the scope of my broader claims.

In the drawings, Fig. 1 is a longitudinal horizontal sectional view, partly broken away, of one form of the structure embodying the present invention;

Fig. 2 is a side elevation;

Fig. 3 is a front elevation illustrating the guards for the flow passages;

Fig. 4 is a transverse sectional view on the line IV—IV of Fig. 1; and

Fig. 5 is a transverse sectional view on the line V—V of Fig. 1.

In carrying out the present invention, there may be provided a boat hull 2 of any desired general construction and contour depending upon the use to which the boat is to be put. The forepart 3 of the hull is a special construction of such nature as to accommodate the means of propulsion in accordance with the present invention. The forepart is preferably provided with a pair of flow passages 4 and 5, respectively, having individual inlets 6 and 7 and individual discharge outlets 8 and 9. At some point intermediate their lengths, the passages preferably intersect to provide a chamber 10 common to both forwardly and rearwardly extending passages and of such cross sectional contour, as indicated more particularly in Fig. 4, as to accommodate a control means 11.

Located in the passage 4 is a flow producing means 12 preferably adjacent the inlet 6, and adapted to be driven in any desired manner, as, for example, by a motor 13. The passage 5 is provided with a similar flow producing means 14 with its driving motor 15. It will be understood that separate driving motors, as herein shown, may be utilized, or that a single driving motor with suitable gearing, as well understood in the art, may be substituted.

With the construction illustrated, assuming that it is desired to move the vessel forwardly in the direction indicated by the arrow A in Fig. 1, the flow producing means 12 and 14 will be rotated in such direction as to produce a water flow through the passages 4 and 5 in the direction indicated by the arrows a. If it is desired to advance the vessel in a straight line, the control means will be placed in the position indicated in full lines in Fig. 1, whereby each flow producing means will effect a discharge of water from its respective outlet. Initially such flow will

be in a general outward and rearward direction, the outward components of the respective streams offsetting one another, whereby the vessel will tend gradually to move forwardly. As the forward movement commences, there will be a relative movement of the water in which the vessel is travelling with respect to the vessel, as indicated by the arrows B. The normal discharge from the respective flow passages will be along the general lines indicated by the arrows B'. This will produce a resultant, indicated generally by the arrows b, the resultant being of gradually increasing effectiveness for propelling purposes as the speed of the vessel increases.

Inasmuch as the water for producing the propelling streams is drawn from the region immediately in front of the vessel, the resistance to forward motion, such as ordinarily encountered with tow-boats which tend to pile up the water on their bows, is minimized. In addition to this, the discharge of water from the respective passages has been found in actual practice to produce a flow along the hull of such nature that the skin friction is materially reduced. The bow waves established by a boat of the construction herein shown when operated at minimum speeds or above is rearwardly in the general direction indicated by the arrows c, thereby clearing any barges which the vessel may have in tow. It is customary to secure barges by comparatively short lines directly to the stern of the boat. In such cases, the absence of any wake, such as produced by the ordinary means of propulsion, assists materially in the progress of the tow through the water, experience having demonstrated that with ordinary tow-boats, the wash from the tug as well as the rearward discharge from the propellers impedes the progress of the barges through the water.

If it is desired to reverse the direction of travel of the vessel while maintaining a substantially straight-line movement thereof, it is only necessary to reverse the direction of rotation of the flow-producing means 12 and 14.

In many cases, where a vessel has been warped into position against a dock or the like, it is desirable in getting under way to produce a flanking movement of the vessel. It may be assumed, for example, that it is desired to produce such flanking movement in the general direction indicated by the arrow F in Fig. 1. In such case the control means 11 will be moved into the dotted-line position f of this figure, whereby the combined flow produced by both of the means 12 and 14 will be directed through the passage 5 and the outlet 9. Since, at this time, there is no forward component of the vessel to be considered, the discharge will be effective for producing a relative flanking movement accom-

panied by a slight forward movement of the vessel which, under normal circumstances, is not objectionable. Where such a forward motion is objectionable, the control 11 may be maintained in its full-line position of Fig. 70 1, the flow-producing means 14 operated to produce a discharge through the outlet 9, and the flow-producing means 12 operated in the reverse direction to produce a discharge through the inlet 6, thereby counteracting 75 the tendency of the craft to move forwardly. By controlling the relative speeds of the individual flow-producing means, an exact component of the lateral or combined lateral and forward motion, or of combined lateral 80 and rearward motion, can be produced.

The vessel also lends itself to turning as will be readily apparent by those skilled in the art. By maintaining the control in its full-line position, and operating the flow-producing means at the same relative speeds, but in opposite directions, the vessel may be turned on a comparatively short radius and in either direction.

By locating the passages entirely in the 90 forepart of the hull, which represents only a comparatively small part of the total length of the vessel, its load carrying capacity is not materially interfered with and its buoyancy is substantially preserved. Also, such an arrangement lends itself to an advantageous 95 positioning of the propelling motors, such as is ordinarily not obtainable with passages extending the entire length, or substantially the entire length, of the hull.

It frequently happens with shallow draft vessels of the type predominating on our inland rivers that a sand bar or other temporary formation is encountered. In such cases the construction herein disclosed may be utilized as a dredge, the flow of water into the flow passages displacing the sand and discharging it rearwardly and laterally. In case the vessel is pulling a wide tow, the dredging action may be continued, accompanied with flanking movements of a sufficient extent to provide a passage of the width required for the vessel and its tow.

In view of the location of the flow producing means 12 and 14, it is obviously necessary to provide suitable means for protecting the inlets 6 and 7 against floating or submerged débris. For this purpose, each of the inlets is protected by guards 16 all of which extend in the same general direction 115 as is apparent from Figs. 1 and 2. The rearward inclination of these guards tend to throw such débris outwardly and toward the rear of the vessel, and the absence of any oppositely extending guards permits such 120 movement. The inlets are thus automatically cleaned to permit the free ingress or egress of water to or from the flow producing means.

In case of failure of one of the motors 130

or of one of the propellers from any cause whatsoever, it is possible to navigate the vessel straight ahead by placing the control in an intermediate position. In chain lines 5 in Fig. 1 the control is shown in the position which it will occupy in the event the motor 15 or the propeller 14 is not suitable for continued duty. In this position the continued operation of the propeller 12 will produce a 10 stream of water which will be divided substantially equally by the control positioned as indicated in chain lines, thereby producing a substantially equal discharge from both of the discharge outlets 8 and 9.

15 It will be understood that in case the shafts are positioned as indicated in the drawings, it will be necessary to provide the control with a recess 17 to permit movement thereof into its dotted-line positions.

20 I have also found that desirable results will be obtained by the provision of compartments 18 in the head of the vessel and preferably on opposite sides of the propelling means. Where such a construction is provided, the vessel will be trimmed with these 25 compartments empty. Thereafter when it becomes desirable to provide extra depth of water to permit free passage of a tow or of the vessel itself, suitable ballast may be 30 placed in the compartments. This will result in untrimming the vessel to the extent that the bow end will be lowered, thereby permitting the sand dredging action, before referred to, to be carried on at a greater 35 depth below the level of the water than would normally be possible. In actual practice, water will probably be utilized as the medium of obtaining the desired additional weight in the head end of the vessel. This 40 may be conveniently pumped out in any suitable manner when it is desired to retrim the vessel.

Certain advantages of the present invention arise from the provision of a propelling 45 means which may be utilized by itself or as an adjunct to standard methods of propulsion now in vogue.

Other advantages of the invention arise from the provision of propelling and steering 50 means of the character herein contemplated including flow passages located entirely in the forepart of the hull of the vessel or in an extension provided thereon.

Other advantages of the invention arise 55 from the provision of separate flow passages with separate flow-producing means, the passages and flow producing means being of such nature as to permit all the water from both flow-producing means to be discharged 60 entirely through one of the passages, equally through both of the passages, or through the two passages in any desired relative proportions depending upon the direction of movement desired.

65 Still further advantages are inherent in

the use of propelling means of such nature that a bank of water in front of the vessel is obviated, the skin friction reduced, and a wake is created such that the resistance to forward travel of the tow is minimized. 70

Still further advantages arise from the use of a propelling means of such nature that it may be utilized for effecting removal of temporary obstructions such as sand bars and the like. 75

I claim:

1. In a boat, a hull, a pair of similar flow passages located entirely in the forepart of said hull and provided with forwardly directed inlets and laterally and rearwardly directed outlets, a flow-producing means in each of said passages, means for driving said flow-producing means in the same or in opposite directions, and a single control common to said flow-producing means, said control means being operative to discharge the water from both of said flow-producing means through one of said passages. 80

2. In a boat, two flow passages intersecting at a point intermediate their ends to form a common chamber, fluid control means in said chamber for effecting any desired division of flow through said passages from nothing to maximum in either direction, and independently variable flow producing 95 means in each passage.

3. In a boat, flow passages intersecting at a point intermediate their ends to form a common chamber, flow-producing means in each passage, and fluid control means in said chamber cooperating with said flow producing means to effect delivery of water to both of said flow-producing means entirely through one of said passages or through both of said passages in any proportion from minimum to maximum and to effect discharge from both of said flow producing means entirely through one of said passages or through both of said passages in any amount from minimum to maximum. 100

4. The combination with a boat having two flow passages in the bow thereof intersecting at a point intermediate their ends to form a common chamber, fluid control means in said chamber for effecting any desired division of flow through said passages from nothing to maximum in either direction, and independently operable flow-producing means in each passage. 115

5. The combination with a boat having two flow passages in the bow thereof intersecting at a point intermediate their ends to form a common chamber, fluid control means in said chamber for effecting any desired division of flow through said passages from nothing to maximum in either direction, and independently operable flow-producing means in each passage located forwardly of said chamber. 125

6. The combination with a boat having 130

two flow passages in the bow thereof intersecting at a point intermediate their ends to form a common chamber, fluid control means in said chamber for effecting any desired division of flow through said passages from nothing to maximum in either direction, flow-producing means in each passage, and means for simultaneously operating said flow-producing means either in the same or in different directions. In testimony whereof I have hereunto set my hand.

10
